FLUID DISPENSING DEVICE

Thomas E. Madden, Newark, N. J.

Application January 14, 1932, Serial No. 586,515

7 Claims. (Cl. 101—125)

My invention relates to improvements in fluid dispensing devices, such as self-inking stencil stamps, lubricating appliances, greasing pads, and similar articles, where the fluid is dispensed through a cushion-like medium for application as required, and while the invention is disclosed in the accompanying drawing in its application to a magazine stencil stamp, it will be readily understood that by substituting oil or grease for the ink, and by eliminating the stencil, the device may be used for greasing a pan or plate for cooking wheat-cakes, and the like, for lubrication, and for various other purposes.

Referring to said drawing, Fig. 1 illustrates in perspective, parts being broken away, a suitable application of my invention as applied to a self-inking stencil stamp. Fig. 2 is a longitudinal section of the same with the magazine handle removed, and Fig. 3 is a longitudinal section illustrating part of the outer frame or retaining means for holding an interchangeable stencil in position.

In the preferred embodiment of my invention a rectangular frame 4 of suitable material, such as wood, is first formed after which a perforated plate or spreader 5 is laid thereon, followed by a piece of felt 6, after which a thicker piece of felt 7 may be applied, and over this is preferably applied two thicknesses of cotton flannel 8, or other suitable material, and finally a piece of thin silk 9. The thicker piece of felt 7 is preferably of slightly less width and length than the other parts so that when the outer fabrics are applied, they may be drawn down around the margins of the piece of felt 7 and held there by metallic frame 10, through which nails 11 may be introduced, securing the same to the wooden frame 4, or, if desired, in lieu of the nails, rivets may be employed, passing through the metal frame 10 and the back of the chamber 12. The chamber 12 is a rectangular, metallic, tray-like structure, having upwardly projecting sides cut away at the corners so that after the pad and frame, assembled as stated, have been inserted therein, as shown in Fig. 2, the marginal portions 13 are bent over at all four sides, thereby securely holding the assembled pad and frame in position within the tray or chamber 12.

At the center of the tray chamber a threaded stud 14 is secured to receive the threaded hollow handle 15 containing the ink, and after the stamp has been assembled as stated, a perforated paper stencil 16, such as are made on the typewriter and used in mimeograph machines, and the like, is laid over the face of the pad, after which the

frame, shown in Fig. 3, with an open center and marginal flange 17, is pressed on over the stencil, the sides 18 being curved inwardly, as indicated at 19, to snugly engage over the rounded shoulders 20 of the tray chamber 12, thus snugly holding the stencil flat against the pad, so that when the stamp is applied, the ink from the magazine handle 15, passing through the perforated plate 5, and felt and fabrics, passes through the cutout portions of the stencil, and faithfully reproduces the desired printed matter. For re-charging the stamp with ink, the handle is readily unscrewed, filled with ink, and re-applied, the top disc-like portion 21 being flexible and forcing the ink through the fabric and felt of the stamp when applied. To replace the stencil, the outer frame 22 is easily removed by spreading the end extensions 19, after which the stencil may be readily removed and replaced with a newly cut stencil according to requirements. This arrangement has been found to provide a very simple, economic and quickly arranged combination of parts, which provides excellent printing and is easily changed from day to day as may be required.

Of course, it will be readily understood that various modifications may be made in the construction and arrangement of parts without departing from the spirit of the invention as claimed.

I claim:

1. In a stamp of the class described, an ink receptacle having a separable frame therefor, an independent open work member at one side of said frame, and absorbent material at the opposite side of said member, means for penetrating and securing said frame, member, and material secured together, at their adjacent margins and an outer frame adapted to be removably secured adjacent thereto.

2. In a stamp of the class described, an ink receptacle having a frame, an open work member at one side of said frame and absorbent material at the opposite side of said member, means for penetrating and securing said frame, member and material secured together, and an outer frame adapted to be removably secured to said receptacle outside said secured parts.

3. In a stamp of the class described, an ink receptacle having a separable frame, a removable flat open work member at one side of said frame and absorbent material at the opposite side of said member, means for penetrating and securing said frame, member, and material together, an outer frame adapted to be removably secured

to said container outside said secured parts, and a stencil intermediate said secured parts and said outer frame.

4. In a device of the class described, a five-sided chamber, a flat spreader therein, framing means for separating said spreader from the base of said chamber, a bed of fibrous material at the outer side of said spreader, a piece of woven material over said fibrous material, means for penetrating and securing said parts together, an outer frame, a stencil between said outer frame and said woven material, said chamber having projecting marginal walls adapted to be turned over upon the margins of said woven material.
5. In a device of the class described, a five-sided chamber, a flat spreader therein, a frame for separating said spreader from the base of said chamber, a bed of fibrous material at the outer side of said spreader, a piece of woven material over said fibrous material, means for penetrating and securing said parts together, an outer frame, a stencil between said outer frame and said woven material, said chamber having projecting marginal walls adapted to be turned over upon the margins of said woven material, said

frame turned over marginal walls of said chamber and the margin of said woven material.

6. In a stamp of the class described an ink receptacle having a separable frame, an open work member at one side of said frame and absorbent material at the opposite side of said member, means penetrating and securing said frame, member and material together, and a removable outer frame having inturned flanges adapted to be secured adjacent said inner frame 10 outside said secured parts.

7. In a stamp of the class described, an ink receptacle having a separable frame, a removable flat open-work member at one side of said frame and absorbent material at the opposite side of 15 said member, means penetrating and securing said frame member and material together, an outer frame adapted to be removably secured adjacent said receptacle outside said secured parts, a second outer frame having an inturned 20 projecting marginal flange engaging the margin of said material, and means extending upwardly from the sides thereof for engaging the upper part of said stamp.
